US0D1056720S

(12) **United States Design Patent** (10) **Patent No.:** **US D1,056,720 S**
(45) **Date of Patent:** **** Jan. 7, 2025**

(54) **CONTAINER**

(71) Applicant: **Henkel AG & Co. KGaA**, Düsseldorf (DE)

(72) Inventors: **Arseni Radomyselski**, Ridgefield, CT (US); **Elizabeth Anne Santarelli**, Westport, CT (US)

(73) Assignee: **Henkel AG & Co. KGaA**, Düsseldorf (DE)

(**) Term: **15 Years**

(21) Appl. No.: **29/879,061**

(22) Filed: **Jun. 30, 2023**

(51) LOC (15) Cl. **09-01**

(52) U.S. Cl.

USPC **D9/530**; D9/682

(57) **CLAIM**

The ornamental design for a container as shown and described.

DESCRIPTION

FIG. 1 is a top, front isometric view of a container showing the claimed design;

FIG. 2 is a bottom, rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dashed broken lines in the figures show portions of the container that form no part of the claimed design.

The dot-dash broken lines in the figures show boundaries that form no part of the claimed design.

1 Claim, 6 Drawing Sheets
